UNITED STATES PATENT OFFICE.

ARTHUR S. S. FUSSELL, OF PHILADELPHIA, PENNSYLVANIA, ASSIGNOR TO JOHN F. SIMONS AND THOMAS MADDOCK, OF SAME PLACE, FREDERIC M. SIMONS, OF SWARTHMORE, PENNSYLVANIA, AND EDWARD S. SIMONS, OF ORANGE, NEW JERSEY, (TRADING AS SIMONS BRO. & COMPANY.)

DESIGN FOR A RING.

SPECIFICATION forming part of Design No. 34,773, dated July 16, 1901.

Application filed June 12, 1901. Serial No. 64,339. Term of patent 7 years.

To all whom it may concern:

Be it known that I, ARTHUR S. S. FUSSELL, of the city and county of Philadelphia, State of Pennsylvania, have invented a new and original Design for a Ring, of which the following is a specification.

My new design for rings is shown in the accompanying drawings, in which—

Figure 1 is a perspective view of a ring embodying the design. Fig. 2 is a plan or face view of the same, and Fig. 3 is a side view.

The ring is of the usual signet form, and the design resides in the ornamentation applied thereto. This ornamentation consists of the

representation of a clock-face *a* upon the face 15 of the ring and the representation of an elk's head *b* on each side adjacent to the face.

What I claim as new, and desire to secure by Letters Patent, is—

The design for a ring substantially as described and shown in the accompanying drawings.

In testimony of which invention I have hereunto set my hand.

ARTHUR S. S. FUSSELL.
